UNITED STATES PATENT OFFICE.

JULIUS FRELLOEHR, OF NEW YORK, N. Y.

INTERNAL-COMBUSTION ENGINE.

Application filed February 21, 1920. Serial No. 360,390.

To all whom it may concern:

Be it known that I, JULIUS FRELLOEHR, a citizen of the United States, residing at the city of New York, borough of Manhattan, in the county and State of New York, have invented certain new and useful Improvements in Internal-Combustion Engines, of which the following is a full, clear, and exact specification.

10 This invention relates to improvements in internal combustion engines, and has for its object to provide an engine which will be efficient in operation.

Further, the invention has for its object 15 to provide an engine in which the cylinder may at will be held stationary or be permitted to rotate.

Further, the invention has for its object 20 to provide an engine in which both ends of the cylinder constitute explosion chambers in order to render the engine double acting.

Further, the invention has for its object 25 to provide an engine in which the length of the stroke of the piston may be readily increased or decreased, as desired.

Other objects will in part be obvious and in part be pointed out hereinafter.

To the attainment of the aforesaid objects and ends my invention consists in the 30 novel details of construction, and in the combination, connection and arrangement of parts hereinafter more fully described and then pointed out in the claims.

In the accompanying drawings forming 35 part of this specification, wherein like reference numerals refer to like parts,

Figure 1 is a sectional view taken on the line 1-1 of Fig. 2, showing an engine constructed according to and embodying the 40 invention;

Fig. 2 is a side elevation, parts being broken away;

Fig. 3 is a plan view, parts being broken away;

45 Fig. 4 is an enlarged detail view of a portion of the driving mechanism, and

Fig. 5 is a detail perspective view of the valve operating mechanism.

Referring to the drawings, 10 designates a 50 frame comprising upwardly extending standards 11, and 12, the standard 11 being provided at its upper end with a hollow bearing 13, and the standard 12 being provided with two bearings 14 and 15, of which the bearing 14 is of greater diameter than the bearing 15. The bearings 14 and 15 have

keyways 16 and 17, respectively, formed therein for a purpose hereinafter described. A supply pipe 18, leading from the source of fuel supply, communicates with the hollow 60 bearing 13.

Supported upon the standards 11 and 12 is a cylinder 19, to one side of which is secured a hollow shaft or trunnion 20 journaled within the hollow bearing 13 and provided with an opening 21 communicating with the interior of the bearing 13. Secured to the opposite side of the cylinder 19 are brackets 22, 22, which carry a plate 23 provided with a sleeve 24 journaled within 70 the bearing 14 on the standard 12, and having a keyway 24' formed therein adapted to register with the keyway 16 in the bearing 14 when the cylinder 19 is in its horizontal position.

75 Reciprocatingly mounted within the cylinder 19 is a hollow piston 25, having an elongated slot 26 formed in its wall and registering with the inner end of the hollow shaft 20, whereby fuel will be admitted constantly into the interior of the piston 25 during the operation of the engine. Spring pressed valves 27, 27, positioned within the ends of the piston 25, serve to control the flow of the fuel from the interior of the piston 25 into the ends of the cylinder 19, as hereinafter explained.

80 Secured to the piston 25, and extending through a slot 28 in the wall of the cylinder 19, is a stud 29, upon the outer end of which is fixed a block 30 provided with laterally extending pins 31, 31, slidingly supported within holes formed in the brackets 22, 22. Formed in the outer surface of the block 30 is a groove 32, adapted to receive a roller 33 carried upon a stud 34 adjustably supported within a slot 35 formed in a disk 36. The disk 36 is fixed to the inner end of a shaft 37 which extends through the plate 23 and the sleeve 24, and 90 is journaled within the bearing 15. The shaft 37 has a keyway 37' formed therein adapted to register with the keyway 17 formed in the bearing 15.

95 Secured to the inner end of the shaft 37, adjacent the disk 36, is a gear wheel 39 meshing with a gear wheel 40 fixed to a shaft 41 rotatably mounted upon the cylinder 19, and carrying cams 42, 43, which are set ninety degrees apart. The cams 42 and 43 100 engage rollers 44, 45, arranged adjacent to the inner slotted ends of valve actuating

members 46, 47, whose outer ends are slid-
ingly mounted within guides 48, 48 carried
by the cylinder 19. The outer ends of the
members 46, 47 are bent inwardly with re-
spect to the cylinder 19, and engage spring-
closed exhaust valves 49, 49, positioned with-
in the heads of the cylinder 19. In the em-
bodiment of the invention shown the gear
wheel 40 has twice as many teeth as has
10 the gear wheel 39.

Pulleys or the like 50 and 51 are secured
to the outer ends of the shafts 20 and 37,
respectively.

By placing a key 52 within the keyways
15 16 and 24', when the same are in register
with one another, the sleeve 24, and, there-
fore, the cylinder 19 will be held against
rotation, whereas, if the key 52 is placed
within the keyways 17 and 37', when in reg-
20 ister with one another, the shaft 37 will be
held against rotation.

The operation of the engine is as fol-
lows:—

Assuming that it is desired to have the
25 cylinder 19 held stationary and to permit the
shaft 37 to rotate, the key 52 is positioned
within the registering keyways 16 and 24',
whereupon, as the piston 25 is reciprocated
within the fixed cylinder 19, the reciproca-
30 tion of the slotted block 30, through the me-
dium of the roller 33 upon the stud 34, will
cause rotation of the disk 36 and of the shaft
37 to which it is secured. Each end of the
cylinder 19 constitutes an explosion cham-
35 ber and the cycle of operations occurring at
each end of the cylinder 19 is the same that
takes place in an engine of the usual four
cycle type, it being understood that the vari-
ous parts are so adjusted and arranged that
40 the several operations occurring at one end
of the cylinder take place a half of a revolu-
tion behind the corresponding operations at
the other end thereof.

After the burnt gases have been exhausted
45 from either end of the cylinder 19, as the
piston 25 begins its next stroke, the valve
27, at the corresponding end of the piston
25, will open, thus allowing a fresh charge
of fuel to enter that end of the cylinder 19.
50 During the next stroke of the piston 25, this
charge will be compressed and ignition of
the same will be effected as the piston 25
reaches the end of the stroke, thus causing
the piston 25 to be driven in the reverse di-
55 rection. During the next stroke of the piston
25 one or the other of the valve actuating
members 46, 47 will be actuated to open the
exhaust valve 49 with which it co-acts thus
permitting the burnt gases to be discharged
60 from the end of the cylinder 19, whereupon
the cycle will be repeated.

By varying the position of the stud 34 and
the roller 33 with respect to the slot 35 in
the disk 36, the length of the stroke of the
65 piston 25 may be varied, the stroke being

shortened as the stud 34 is moved inwardly,
and vice versa.

If it is desired to have the cylinder 19 ro-
tate, the key 52 is positioned within the key-
ways 17 and 37' to hold the shaft 37 against 70
rotation. When this is done, the reciproca-
tion of the piston 25, in the manner above
described, will cause the cylinder 19 to ro-
tate, thus effecting rotation of the hollow
shaft 20 and of the pulley 50 carried thereby. 75
When the engine is operating with the cylin-
ders rotating the explosion periods occur
when the cylinders are in the vertical posi-
tion.

Having thus described my said invention, 80
what I claim and desire to secure by Let-
ters Patent is:—

1. An internal combustion engine com-
prising a frame, a shaft composed of a pair
of parts rotatably supported thereon, a cyl-
inder secured to one of said shaft parts, a 85
bracket secured to said cylinder, a sleeve se-
cured to said bracket and enclosing the other
of said shaft parts; said sleeve being ro-
tatably mounted upon said frame, and means
90 to hold either said sleeve or said shaft part
therein against rotation, substantially as
specified.

2. In an internal combustion engine, a cyl-
inder, a shaft secured thereto, a piston with-
in said cylinder, a shaft operatively con-
nected to said piston, a sleeve secured to said 95
cylinder and embracing said second men-
tioned shaft, and means to hold either said
sleeve or said second mentioned shaft against
100 rotation, substantially as specified.

3. In an internal combustion engine, a cyl-
inder, a piston therein, a grooved member
carried by said piston, a shaft, and means
supported by said shaft and slidably engag-
ing the groove in said member, said means
105 being adjustable whereby the length of
stroke of said piston may be varied, sub-
stantially as specified.

4. In an internal combustion engine, a cyl-
inder, a piston therein, a grooved block car-
ried by said piston, a shaft, a disk secured
thereto, and a stud carried by said disk and
engaging the groove in said block, said stud
110 being adjustable whereby the length of
stroke of said piston may be varied, sub-
stantially as specified.

5. An internal combustion engine com-
prising a frame, a shaft composed of a pair
of parts rotatably supported upon said 115
frame, a cylinder secured to one of said shaft
parts, valves in the ends of said cylinder,
a piston working in said cylinder, means for
admitting an explosive mixture to the ends
of said cylinder, a sleeve upon said second-
120 named shaft part and rotatably supported
upon said frame, a member fixed upon the
inner end of said second-named shaft part,
a pin extending from said member, a mem-
ber on said piston extending through said 125
130

cylinder and adapted to receive the pin on said first-named member, and means operated by said second-named shaft part for actuating said valves, substantially as specified.

6. An internal combustion engine comprising a frame, a shaft composed of a pair of parts rotatably supported upon said frame, a cylinder secured to one of said shaft parts, valves in the ends of said cylinder, a piston working in said cylinder, means for admitting an explosive mixture to the ends of said cylinder, a sleeve upon said second-named shaft part and rotatably supported upon said frame, a member fixed upon the inner end of said second-named shaft part, a pin extending from said member, a member on said piston extending through said cylinder and adapted to receive the pin on the member fixed upon said second-named shaft part, means for guiding the member on said piston longitudinally of said cylinder, and means operated by said second-named shaft part for actuating said valves, substantially as specified.

7. An internal combustion engine comprising a frame, a shaft composed of a pair of parts rotatably supported upon said frame, a cylinder secured to one of said shaft parts, said cylinder having a longitudinal slot therein, valves in the opposite ends of said cylinder, a piston working in said cylinder, means for admitting an explosive mixture to the ends of said cylinder, a member secured to said piston and extending through the longitudinal slot in said cylinder, a slotted member secured to the outer end of said member, a sleeve disposed upon said second-named shaft part and rotatably supported upon said frame, a disc fixed upon the inner end of said second-named shaft part, a pin adjustably mounted upon said disc, adapted to engage the slotted member on said first-named member, a gear on said second-named shaft part, a shaft supported transversely upon said cylinder, a gear on said last-named shaft meshing with the gear on said second-named shaft part, a pair of valve-operating members mounted upon said cylinder and engaging the valves in the ends thereof, and cam means on said shaft adapted to actuate said valve-operating members, substantially as specified.

8. An internal combustion engine comprising a frame, a shaft composed of a pair of parts rotatably supported upon said frame, a cylinder secured to one of said shaft parts, said cylinder having a longitudinal slot therein, valves in the opposite ends of said cylinder, guides mounted on the ends of said cylinder, valve-operating rods supported in said guides, studs at the

inner ends of said valve-operating rods, a piston working in said cylinder, means for admitting an explosive mixture to the ends of said cylinder, a member secured to said piston and extending through the longitudinal slot in said cylinder, a block secured to said member having a longitudinal slot therein, a sleeve disposed upon said second-named shaft part and rotatably supported upon said frame, means for locking said sleeve member with respect to said frame, a disc fixed upon the inner end of said second-named shaft part, a pin adjustably mounted upon said disc adapted to engage with the slot in the member carried by said piston, a gear on said second-named shaft part, a bearing mounted upon the cylinder and arranged transversely intermediate the ends thereof, a shaft mounted in said bearing, a gear on said shaft meshing with the gear on said second-named shaft part, and cams fixed upon said shaft cooperating with the stops upon said valve-operating rods whereby to actuate said valves, substantially as specified.

9. An internal combustion engine comprising a frame, a shaft composed of a pair of parts rotatably supported upon said frame, a cylinder secured to one of said shaft parts, said cylinder having a longitudinal slot therein, valves in the opposite ends of said cylinder, guides mounted upon said cylinder, valve-operating rods supported in said guides, brackets upon said cylinder, a plate secured to the ends of said bracket, a sleeve member secured to the plate and rotatably mounted in said frame and enclosing the other of said shaft parts, a piston working in said cylinder, means for admitting an explosive mixture to the ends of said cylinder, a member secured to said piston and extending through the longitudinal slot in said cylinder, a block secured to said member having a longitudinal slot therein, guides arranged upon the opposite sides of said block and extending through said brackets, means for severally locking said sleeve member and said shaft part therein with respect to said frame, a disc fixed upon the inner end of said second-named shaft part, a pin adjustably mounted upon said disc adapted to engage with the slot in the member carried by said piston, and means operated by said second-named shaft part for actuating said valve-operating rods, substantially as specified.

Signed at the city of New York, borough of Manhattan, in the county and State of New York, this first day of August, One thousand nine hundred and nineteen.

JULIUS FRELLOEHR.
